SLUB DETECTOR

Filed Oct. 25, 1930

By his Attorney
John Reinhard.

UNITED STATES PATENT OFFICE

EDWARD BLOOM, OF PATERSON, NEW JERSEY

SLUB DETECTOR

Application filed October 25, 1930. Serial No. 491,125.

The principal object of this invention is to provide the yarn-traversing means of any machine, as a winding machine, in which the yarn while being drawn lengthwise is traversed crosswise of itself with a slub-detector so cooperative with the said traversing means that the cutting or forming of nicks in the detector as an incident of the travel of the yarn in contact therewith, taken with the traverse 10 of the yarn, will be so considerably postponed as to make it practicable to employ a slub-detector in such a mechanism. Heretofore the detecting of slubs in a mechanism of the class indicated where traverse of the yarn 15 was effected has been regarded as impracticable because the traverse induced the cutting of nicks in the detecting edges of the slub-detector by the travelling yarn and consequently the catching of the yarn in such nicks and its 20 being therefore broken.

My invention is not limited in its application to instances where the yarn is actually traversed. It applies, as will be apparent, in any instance where the travelling yarn 25 exerts pressure on the detector tending to displace it crosswise of the yarn and so promotes the forming of the nicks.

In the drawings,

Fig. 1 shows in side elevation sufficient of 30 a winding machine containing the invention to illustrate the latter;

Fig. 2 is a plan thereof on a smaller scale;

Fig. 3 is a rear elevation of the traverse 35 means and the slub detector; and

Fig. 4 a side elevation thereof, with said means partly in section.

The winding machine shown is of a well known type. 1 is its frame; 2 brackets therein to support the revoluble thread aperture, here a core on which the yarn *a* is wound, such core here comprising a spindle 3 having a whirl 4 and carrying the spool 5 to receive the windings; 6 a suitably rotated driving wheel on which the whirl 4 rests and by which the core is rotated; and 7 a yarn-traversing rail suitably reciprocated in the frame lengthwise of itself and crosswise of the yarn and having a yarn-guide 8 provided with a yarn-receiving notch 9. The core and wheel 45 form the aforesaid means to draw the yarn

lengthwise and the rail affords the aforesaid means to traverse the yarn crosswise.

A support in the form of a plate 10 is here secured to the back of the rail—to wit, the side adjoining the core for the windings—by screws 11, it being provided with slots 12 extending, and thus permitting adjustment of the support and hence of the slub-detector carried by the support, lengthwise of the rail. It may have a flange 13 to rest on the top of the rail and a pair of spaced stops 14. The plate has a rearward projecting headed stud or pivot 15 in the vertical plane of the notch 9 of the yarn guide 8.

The slub-detector is an elongated plate 16 having a notch 17 in one end communicating with a slub-detecting slit 18 extending lengthwise of the plate. Nearer the notched than the other end of the plate is a bearing 19 formed as one end of a key-hole slot 20 adapted to receive the pivot 15; when the slub-detector is thus supported on the pivot it hangs normally in the position of Fig. 3, with its notched end up, due to gravity acting on its longer lower end portion. It is, however, free to swing back and forth laterally, at least as far as the stops 14 will permit.

Operation: The detector in the example illustrated is in effect a pendulum, so that it tends to stand vertically. As the rail reciprocates in traversing the yarn exerts pressure on one side or the other of the detector slit, according as said side is the relatively following one of the two. If the detector were rigidly mounted on the rail the frictional contact of the travelling yarn with such side would produce a nick therein, which sooner or later will catch and break the yarn. But according to my construction the detector yields to the yarn, and such yielding in itself delays the cutting of such nicks. But, in addition, the detector's movement in yielding, because the detector is pivoted, is not only lateral but downward (that is to say, crosswise of the yarn as well as of the traverse), whereby the yarn shifts its position along the side of the slit against which it is caused to bear due to the displacement thereof by the rail.

In this example the detector is mounted 100

on the rail; but that is obviously not indispensable.

In this example, further, and according to a well known system characterizing winding machines of the class shown, the traverse action on the yarn is from a plane cutting the spool centrally toward each end thereof; wherefore as stated the detector yields to the yarn in the traverse of the rail in opposite directions from said plane. However, the invention is not limited to the traverse motion imparted to the yarn and the consequent yielding of the detector being thus alternately in opposite directions, as the appended claims indicate.

Again, in the example the slub detector is normally urged (here by gravity) to a given position; but that, also, is not indispensable.

It is further new to combine means to draw yarn lengthwise of itself, means to traverse the yarn crosswise of itself, and a slub detector having a yarn-engaging slub-detecting side (as one side of slit 18) extending crosswise of the yarn and also of the traverse and such detector movable (by the yarn or otherwise) crosswise of the yarn and also of said traverse, and I claim the same broadly.

Having thus fully described my invention what I claim is:

- 30 1. In combination, a support and a slub detector carried thereby and having an aperture to receive the yarn and normally held in a given position but yieldable therefrom on the support in opposite directions crosswise of and to the yarn while the latter is drawn lengthwise of itself.
- 20 2. In combination, a support and a pendulum slub detector carried thereby and having an aperture to receive the yarn.
- 30 3. Mechanism of the class described comprising means for drawing the yarn lengthwise of itself, means for traversing the yarn crosswise of itself and a slub detector engaged by the yarn and forming an independently movable part of said mechanism yieldable to the yarn in one direction of its traverse motion.
- 40 4. Mechanism as set forth in claim 3 and in which the detector is normally urged in the opposite direction.
- 45 5. Mechanism as set forth in claim 3 and in which the detector is carried by the traversing means.
- 55 6. Mechanism as set forth in claim 3 and in which the detector is carried by the traversing means and is normally urged in the opposite direction.
- 60 7. Mechanism as set forth in claim 3 and in which the detector is movable as defined in said claim around a pivot.
- 65 8. Mechanism as set forth in claim 3 and in which the detector is movable as defined in said claim on the traversing means and around a pivot.
- 70 9. Mechanism as set forth in claim 3 and

in which the detector is movable as defined in said claim on the traversing means and around a pivot and is normally urged in the opposite direction.

10. Mechanism of the class described comprising means for drawing the yarn lengthwise of itself, means for traversing the yarn crosswise of itself, and a slub detector having a yarn-engaged slub-detecting side extending crosswise of the yarn and of the traverse, said detector forming a part of said mechanism movable independently crosswise of the yarn and of said traverse.

11. Mechanism of the class described comprising means for drawing the yarn lengthwise of itself, means for traversing the yarn crosswise of itself, and a slub detector having a yarn-engaged slub-detecting side extending crosswise of the yarn and of the traverse, said detector being pivotally movable around an axis extending substantially lengthwise of the yarn.

12. Mechanism as set forth in claim 10 and in which the detector is carried by the traversing means.

13. Mechanism as set forth in claim 10 and in which the detector is movable as defined in said claim around an axis extending substantially lengthwise of the yarn and is carried by the traversing means.

14. Mechanism of the class described comprising means for drawing the yarn lengthwise of itself, means for traversing the yarn crosswise of itself and a pendulum slub detector engaged by and yieldable to the yarn in one direction of its traverse motion.

15. Mechanism as defined in claim 14 and in which the detector is carried by the traversing means.

In testimony whereof I affix my signature. EDWARD BLOOM.
